OTHER PUBLICATIONS

Hoover Battery Pack, Applicant sold in the U.S. a battery similar to the one illustrated in Appendix A on Mar. 18, 2014.

Primary Examiner — Rosemary K Tarcza

(74) Attorney, Agent, or Firm — Michael Best & Friedrich LLP

(57) **CLAIM**

We claim the ornamental design for a charger, as shown.

DESCRIPTION

FIG. 1 is a front perspective view of a charger, showing a first embodiment;

FIG. 2 is a rear perspective view thereof;

FIG. 3 is a front elevational view thereof;

FIG. 4 is a rear elevational view thereof;

FIG. 5 is a side elevational view thereof;

FIG. 6 is an opposite side elevational view thereof;

FIG. 7 is a top plan view thereof;

FIG. 8 is a bottom plan view thereof;

FIG. 9 is a front perspective view of a charger, showing a second embodiment;

FIG. 10 is a rear perspective view thereof;

FIG. 11 is a front elevational view thereof;

FIG. 12 is a rear elevational view thereof;

FIG. 13 is a side elevational view thereof;

FIG. 14 is an opposite side elevational view thereof;

FIG. 15 is a top plan view thereof; and,

FIG. 16 is a bottom plan view thereof.
